OSTOMY DRAINAGE BAG

Marvin Katzman, 1520 202nd St., Bayside, N.Y. 11360,
and Neil De Fluri, 952 Arnet Ave., Union, N.J. 07083

Filed Jan. 21, 1974, Ser. No. 435,121

Term of patent 14 years

Int. Cl. D24—03

U.S. Cl. D83—1 P

FIG. 1

FIG. 2

FIG. 3

FIG. 4

FIG. 5

FIG. 1 is a rear view of an ostomy drainage bag incorporating our new design;

FIG. 2 is a front view of the ostomy drainage bag shown in FIG. 1;

FIG. 3 is a right-hand side elevation of the ostomy drainage bag shown in FIG. 1, which is a mirror image of the left-hand side thereof;

FIG. 4 is a top plan view of the ostomy drainage bag shown in FIG. 1; and

FIG. 5 is a bottom plan view of the ostomy drainage bag shown in FIG. 1.

We claim:

The ornamental design for an ostomy drainage bag, as shown and described.
